UNITED STATES PATENT OFFICE

2,336,160

ELECTRIC SHAVER

Randolph Boyd, Galva, Ill.

Application September 27, 1943, Serial No. 503,978

6 Claims. (Cl. 30—33)

The invention aims to provide a safety shaver, and a head for a safety shaver, so constructed that, through the instrumentality of a lateral extension, a shaving operation may be carried out closely adjacent to or in the human nose, or in other similarly restricted places.

The invention differs from the many devices used for cutting in or about the nose, in that, in the device forming the subject matter of this application, the instrument is capable of carrying out the usual safety shaver operation, at the same time that the cutting operation is going on in the restricted area.

Another object of the invention is to supply a device of the class hereinbefore alluded to, in which the extension is an integral part of the head of the shaver.

Another object of the invention is to supply a device of the sort under consideration, in which the extension is removable, novel means being supplied for assembling the extension with a main guard and with a main cutter, the extension comprising a supplemental guard and a supplemental cutter.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows, in side elevation, a safety shaver embodying the device forming the subject matter of this application;

Fig. 2 is a transverse section wherein the handle of the shaver remains in elevation, parts being broken away;

Fig. 3 is an end elevation;

Fig. 4 is a side elevation showing a modification;

Fig. 5 is a side elevation wherein parts are shown in longitudinal section;

Figs. 6 and 7 are sections taken respectively on lines 6—6 and 7—7 of Fig. 5;

Fig. 8 is a section on the line 8—8 of Fig. 7.

In the drawings there is shown a safety shaver comprising an elongated handle 1, supplied in one end with a transverse recess 2. The handle 1 encloses an electric motor (not shown), deriving current from a conductor 3. The motor operates or includes a shaft 4, provided at its outer end with an eccentric 5. A set screw 6 is

threaded into the handle 1 and is adapted to enter the recess 2. The starting wheel is indicated at 7.

The structure which characterizes the present invention may be used with such a handle and associated parts, and the handle and associated parts may form part of the general combination, although the device hereinafter described may be used with a handle differing from that described.

There is provided a head H, comprising an elongated base 8, shaped to fit in the recess 2 of the handle 1 and extended transversely of the length of the handle. The base 8 of the head H is supplied with a seat 9, adapted to receive the inner end of the set screw 6, in order to hold the head in the recess 2.

The base 8 of the head H carries a tubular guard 10, prolonged outwardly beyond one lateral end surface 11 of the base, to define an extension 12. The extension 12 is disposed approximately at right angles to the longitudinal axis of the handle 1. The extension 12 is tapered at its outer end, to any desired extent, as indicated at 25, so as to be readily insertible in the nostril.

The head H includes a power actuated cutting mechanism extended substantially across the end of the handle and substantially to the outer end of the part 12.

30 The cutting mechanism includes an elongated tubular member 14, mounted in the guard 10 for longitudinal reciprocation and for a slight rocking movement, the said member projecting into the prolonged portion or extension 12 of the guard 10.

The movable member 14 and the guard 10 have cooperating parts 15 defining a cutting mechanism extended practically throughout the length of the guard and its prolonged portion 12.

40 The movable member 14 has an opening 16, receiving the eccentric 5 on the shaft 4, and, thus motion is imparted to the member 14, relatively to the guard 10.

The extension 12 and the corresponding part 45 of the movable member 14 are of such length, and of so small transverse dimensions, that the portions of the cutting elements 15 upon them can be used in restricted areas, for example, about or in the human nose, which could not be reached by the portion of the cutting elements which extend substantially across the end of the handle 1.

The extension 12 and associated parts may be used alone, in the manner hereinbefore pointed out; or, while the operator is using the cutting parts that extend across the end of the handle 1, he may, at the same time, use the cutting parts of the extension 12, to work in places on the human face that are not readily accessible otherwise. This clearly differentiates the device here-

in disclosed from articles which, even though including parts which seem to be equivalent to the guard 10 and the movable member 14, are adapted to operate on the nose only, and are not associated with such a member as the handle 1. In the applicant's device there is the usual cutting operation at the end of the handle 1, and, if desired, a simultaneous cutting operation produced by the extension 12 and associated parts.

In Figs. 4 to 8, parts hereinbefore described have been designated by numerals already used with the suffix *a*.

In this form of the invention, the extension 12a is removable. It includes a supplemental guard 26, provided at its inner end with a reduced, circumferential flange 27, received in a correspondingly shaped recess 28 in the end of the main guard 10a. In the flange 27 are mounted pins 29, received in bores 30 formed in the guard 10a, the pins and the bores extending longitudinally of the extension 12a and constituting interengaging elements coacting to prevent the supplemental guard 26 from rotating on the main guard 10a.

In its lower surface, the supplemental guard 26 has a longitudinal groove 31 which is intersected by a transverse notch 32 formed in the supplemental guard. A spring latch 33 is located in the groove 31, the outer end 34 of the latch being secured to the supplemental guard 26. The outer end 34 of the latch 33 is secured to the supplemental guard 26, the inner end of the latch being supplied with a transverse head 35, extended across the inner end of the flange 27 and adapted to be received in a keeper recess 36 formed in the main guard 10a.

The latch 33 and the keeper recess 36 constitutes interengaging parts cooperating to hold the supplemental guard 26 on the main guard 10a. The notch 32 in the supplemental guard 26 gives access to the spring latch 33 so that the latch may be sprung outwardly, to disengage the head 35 from the keeper or recess 36. When this condition exists, the supplemental guard 26 may be removed endwise from the main guard 10a.

The numeral 37 marks a supplemental cutting member disposed within the supplemental guard 26. The flange of the supplemental cutting member 37 is shown at 38 and is received in the recess 39 of the main cutting member 14a, the pins carried by the flange 38 appearing at 40, and the bores in the cutting member 14a appearing at 41. More detailed description seems unnecessary, in view of what has been stated hereinbefore respecting the corresponding parts of the supplemental guard 26 and the main guard 10a.

The longitudinal spring latch 41, constructed like the latch 33, is located in the bore of the supplemental cutting member 37 and has its outer end secured to the supplemental cutting member. The head of the latch 41 cooperates with the cutting member 14a, as hereinbefore described in connection with the head 35 of the latch 33.

It is to be observed that the latch 41 is located within the bore of the supplemental cutting member 37 and is not, therefore, superficially accessible, as is the latch 33. In order to provide for a disengagement of the head of the latch 41 from the main cutting member 14a, an opening 42 is formed in the supplemental cutting member 37, transversely thereof, beneath the latch 41. After the supplemental guard 26 has been taken off, as hereinbefore described, any

suitable object may be introduced into the opening 42, to disengage the head of the latch 41 from the main cutting member 14a.

The supplemental guard 26 and the supplemental cutting member 37 have cooperating parts 43, duplicating the cutting parts 14a and constituting a continuation thereof.

What is claimed is:

1. A safety shaver comprising an elongated handle, a head mounted on one end of the handle and provided with an extension prolonged beyond one lateral edge of the handle and disposed approximately at right angles to the longitudinal axis of the handle, the head including power-actuated cutting mechanism extended substantially across said end of the handle and substantially to the outer end of the extension, the extension being of such length, and of so small transverse dimensions, that the portion of the cutting mechanism upon it can be used in restricted areas, for example, about or in the human nose, which could not be reached by the portion of the cutting mechanism which extends substantially across said end of the handle.

2. A head for a safety shaver, comprising an elongated base, shaped to fit in the end recess of a safety shaved handle, transversely of the length of the shaver handle, a tubular guard carried by the base and prolonged outwardly beyond one lateral end-surface of the base, a power-actuated member mounted movably in the guard and in its prolonged portion, the movable member and the guard having cooperating parts defining a cutting mechanism extended practically throughout the length of the guard and its prolonged portion, the extension and the corresponding part of the movable member being of such length, and of so small transverse dimensions, that the portion of the cutting mechanism upon them can be used in restricted areas.

3. A safety shaver comprising an elongated handle, a cutting device at one end of the handle, and means for actuating the cutting device, the cutting device extending far enough beyond one outer, longitudinal edge of the handle to form a lateral portion of such dimensions as to be conveniently usable in the human nostril.

4. A safety shaver comprising a handle, a transverse, main guard at one end of the handle, a transverse, main cutting member mounted to move in the main guard, means for actuating the main cutting member, a transverse supplemental guard, a transverse supplemental cutting member mounted to move in the supplemental guard, a releasable connection between the outer end of the main guard and the inner end of the supplemental guard, and a releasable connection between the outer end of the main cutting member and the inner end of the supplemental cutting member, the supplemental guard and the supplemental cutting member forming a detachable extension shaped to work in the human nostril.

5. A safety shaver constructed as set forth in claim 4, and wherein each releasable connection comprises elements detachably interengaged against rotation, and other elements detachably interengaged against longitudinal movement.

6. A safety shaver constructed as set forth in claim 4, and wherein each releasable connection includes a longitudinal pin and socket structure and a longitudinal latch and keeper structure.

RANDOLPH BOYD.
